(57) **CLAIM**

The ornamental design for an orthopedic rasp for preparing an intercuneiform joint, as shown and described.

DESCRIPTION

FIG. 1 is a perspective view of our new design for an orthopedic rasp for preparing an intercuneiform joint; FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof with cutting teeth on the bottom shown in broken lines.

The broken lines shown on FIGS. 1-7 illustrate portions of the orthopedic rasp for preparing an intercuneiform joint that form no part of the claimed design.
